(57) **CLAIM**

The ornamental design for a medical device, as shown and described.

DESCRIPTION

FIG. 1 shows a perspective view of a design for a medical device.

FIG. 2 shows a front view of the medical device.

FIG. 3 shows a back view of the medical device.

FIG. 4 shows a left side view of the medical device.

FIG. 5 shows a right side view of the medical device.

FIG. 6 shows a top view of the medical device.

FIG. 7 shows a bottom view of the medical device; and, FIG. 8 shows a view of the medical device being gripped by a hand of a user.

The dashed broken line showing of a user's hand in FIG. 8 depicts environmental subject matter and forms no part of the claimed design. All other dashed broken lines in the drawings depict portions of the medical device that form no part of the claimed design. The dot-dash broken lines depict the bounds of the claimed design and form no part thereof.

1 Claim, 8 Drawing Sheets
